(57) **CLAIM**

The ornamental design for a steering wheel pad for automobile, as shown and described.

DESCRIPTION

FIG. 1 is a perspective view from the left side of a steering wheel pad for automobile.

FIG. 2 is a front elevation view thereof.

FIG. 3 is a right side elevation view thereof. A left side elevation view is a mirror image of the right side elevation view; and,

FIG. 4 is a top plan view thereof.

The portions of the steering wheel pad shown in broken lines are for the purpose of showing environmental structure only and form no part of the claimed design.
